CLAIM

The ornamental design for a display for a dishwasher, as shown and described.

DESCRIPTION

FIG. 1 is a front view of a first embodiment of a display for a dishwasher showing our new design;

FIG. 2 is a perspective view thereof;

FIG. 3 is a front view of a second embodiment of a display for a dishwasher showing our new design; and,

FIG. 4 is a perspective view thereof.

The use of stippling in FIGS. 3 and 4 denotes contrast compared to surrounding structure.

1 Claim, 4 Drawing Sheets
